UNITED STATES PATENT OFFICE.

WILLIAM H. APPLEMAN, OF OLEAN, NEW YORK.

SAWMILL LOG-SETTING DEVICE.

1,244,575.

Specification of Letters Patent. Patented Oct. 30, 1917.

Application filed April 30, 1915. Serial No. 25,077.

To all whom it may concern:

Be it known that I, WILLIAM H. APPLEMAN, a citizen of the United States, and a resident of Olean, in the county of Cattaraugus and State of New York, have invented a new and useful Improvement in Sawmill Log-Setting Devices, of which the following is a specification.

My invention relates especially to accurate means for actuating and controlling the movement of what is termed the rocker shaft of such log setting devices, in order to impart proper movement to that portion of the setting mechanism that engages more directly with the setting shaft and head blocks.

The object of my invention is to provide a means for securing greater accuracy in moving the head block knees or standard toward the saw line, greater accessibility to working parts and at the same time eliminate the impact and objectionable inertia found in other machines for a like purpose.

I attain these objects in the mechanism illustrated in the accompanying drawing in which—

Figure 1, is a right side elevation view of my device, assembled in connection with portions of a saw-mill carriage and illustrates its application to same.

Fig. 2, is a rear end elevation of the actuating members shown in Fig. 1.

Fig. 3, is a plan and also sectional view of a sliding guide block outlined in Fig. 1, and also required in Fig. 2.

Fig. 4, is a left side elevation view of my device assembled in connection with a saw-mill carriage, and outlines sufficient members of the usual type of setting mechanism to make its general application fully understood.

Fig. 5, is a side elevation view of the graduating or setting lever shown in Figs. 1, 2 and 4, the near branch of same being removed in order to present an internal view of same.

Fig. 6, is a sectional view of the lower end of Fig. 5 taken radial of the curved portions of same, at its pivotal support and in which the relative positions of the two branches of same are maintained.

Fig. 7, is a rear end elevation of a slight modification of Figs. 1, 2 and 4.

Fig. 8, is a side elevation view of said modification.

Fig. 9, presents both a side elevation view

and sectional elevation view of the link type members shown in Figs. 7 and 8 of said modification.

Fig. 10, is a side, and also end elevation view of a cross head used and outlined in Figs. 1, 2, 4 and 7.

Fig. 11, is a longitudinal sectional view of the cylinder and valve chest of Figs. 1 and 4 of my device, and taken on a vertical plane slightly to the right of line of *a—a* indicated in Fig. 14.

Fig. 12, is a sectional plan view of the upper portions of the cylinder as it would appear, when sectioned horizontally on a line *B—B* in Fig. 11.

Fig. 13, is a plan view of the bottom of the valve chest of Fig. 11 as it would appear if the top of said chest was turned from you.

Fig. 14, is a plan view of the top of the cylinder of Fig. 11 as it would appear where it meets the aforesaid valve chest, and assuming that the top of said cylinder was turned toward you.

Like symbols indicate like or similar parts throughout all of the various figures. The functions of such members as are indicated by dotted lines is so clear as to render them easily understood by any one skilled in the art, or familiar with sawmill appliances.

A carriage frame 1 is provided for supporting my device, as well as for illustrating its application to same, said carriage being mounted on a series of trucks 2, and being equipped with two or more head-blocks 3, each of which in turn is provided with a knee or standard 4, the lower surface of which is provided with a rack 5 which engages with a pinion (not shown) but located within the confines of block 3, on a setting shaft 7, said shaft being of such length as to form a connection between all of the blocks and standards employed. An engine having an extension bed or frame is so mounted on carriage frame 1 as to form a substantial anchor between said carriage frame 1 and setting shaft 7. Said engine

comprises a cylinder 8, having an integral extension base which is so machined as to form a cylindrical guide 8^a. Working in said cylinder is a piston 9, and rigidly attached thereto is a piston rod 10 which passes through a stuffing box 11, and rigidly engages with a cross head 10^a, said cross-head being machined to a sliding fit in guide 8^a, and having an opening 10^b, therein which

carries a pivotal pin 10^a. On top of cylinder 8 is a valve chest 12, fitted with a valve 13 and having an outward extending stem 14, which has means of engagement with an 5 operating lever 15.

On the right side of the engine bed is rigidly attached a skeleton frame piece 16, which at the top thereof supports a pair of circle pieces or quadrant 16^a, having notches 10 covering its entire upper surface. Said frame piece is rigidly secured to said engine bed by bolts 17 and also by bolt 18 which passes through an ear or lug 19, on said frame piece, and also through a corresponding lug on cylinder 8.

Frame piece 16 not only provides a bearing support for the operating valve mechanisms, but is also provided with a pivotal opening 20. Secured to the left hand side 20 of the engine bed and cylinder in like manner, is a second frame piece 21, the side view outlines of which can be distinctly traced in Fig. 1. Said frame piece, however, only extends upward a little above the lower 25 edge of the large circular opening in frame piece 16, and at which point it carries and supports a journal bearing 22. It is also provided with a pivotal opening 20^a, which is in direct alinement with opening 20, in 30 frame piece 16. Still further to the left is a third frame piece 23 which rests on the carriage frame, carries a bearing 24 which receives the setting shaft 7, and also extends upward and supports a bearing 25 in alinement with bearing 22, of frame 21.

Inserted between frame pieces 16 and 21, is a swinging graduating setting lever 26, said lever being forked at its lower end, each branch thereof being provided with 20 stub shafts or trunnions 27 and 28 which rest within the pivotal openings 20 and 20^a in frames 16 and 21 respectively, said openings being located almost on a line with, but slightly below the central line of piston rod 10. The upper end of lever 26 is provided with a latch 29 which is adapted to engage at any desired point on quadrant 16^a, and the lower branches are each provided with a circular guide 30 which face 35 inward or toward each other, in perfect axial alinement.

Mounted in bearings 22 and 25, of frames 21 and 23 respectively, is a shaft 31, usually referred to as the rocker shaft in saw-mill setting devices. Said shaft is fitted with an arm 32, having a crank pin 33 which lies approximately on a level with shaft 31, and also directly at the radial center of guides 30-30. Pivotedly attached to crank pin 33 38 is a depending link 34, having a boss 35, and pivotal opening 36, at its lower end. Pivotedly attached to the cross-head extension 10^a of piston 10, by a pivotal pin 10^a, is a forked or two piece connecting rod or 45 link 37, the outer end of which is pivotally

attached to link 34, by a pivotal pin 38. Connecting link 34 and rod 37, however, are of such length that when all parts are in the position shown, the center of pin 38, stands directly on a line with the axis of trunnions 27 and 28 of lever 26. Pin 38 in addition to passing through said connecting rod and link, also extends beyond the outer forked end of rod 37 at both sides thereof, and enters into guide chambers 30 their full 75 depth, and each of said extensions within said guides are pivotally provided with a guide block 39, which is machined to a sliding fit in said guide 30. Therefore, it will be observed that pin 38 brings the center 80 of guide block 39, the center of the joined ends of links 34 and rod 37 and trunnions 27 and 28, of the setting lever, all directly in line. Lying between frames 21 and 23 are the usual members of an ordinary setting mechanism, comprising a pair of wheels 40 and 41 which are rigidly attached to setting shaft 7. Pivotedly attached to shaft 7 and encircling each of said wheels are swinging pawl carriers 42 and 43, each 85 being fitted with gripping devices adapted to engage with said wheels 40 and 41 while swinging in one direction and release while swinging in the opposite direction. A double rocker arm 44 is attached to rocker shaft 90 31 in such position as to bring its arms directly in line with said pawl carriers. A link 45 connects the upper arm of said rocker with pawl carrier 43, and a similar link 46 connects the lower arm of said 100 rocker with pawl carrier 42. (Shafts 47 and 48 relate to receding mechanism not shown nor involved in my application.)

The operation of my device is exceedingly simple. All parts are shown in what is termed a home position. Moving the valve lever 15 toward cylinder 8 or away from the operator, admits steam to the far or outer end of cylinder 8, causing piston 9 and rod 10 with cross head 10^a, to move toward the operator, and inasmuch as the outer end of connecting rod 37, lower end of link 34, and the two guide blocks 39, are all pivotally secured to each other by pin 38, they must naturally be guided by the 115 course of said guide blocks and which travel outward and upward on the arc-shaped guides 30 as the piston rod moves outward, and also return to their former position when the piston is returned to its home position.

Now if the foregoing movements are effected with lever 26 in the home position shown, pivotal bolt 38 with its attached members merely describes an arcuate movement from point *a* to point *b* (see diagram Fig. 5) having its center directly in line with the center of crank pin 33, and therefore, no movement whatever is imparted to said crank, or through it to rocker shaft 31. 130

If, however, lever 26 be rocked forward to the dotted position shown in Fig. 1, the upper end of guides 30 are also rocked forward, thereby carrying their radial center (which with lever 26 is imaginary only) from the center of crank 33 to cross *e* of said diagram, Fig. 5, and the outward movement of the piston will cause pin 38 to travel on a radial line which begins at cross *a* and 10 terminates at cross *e*, and during which crank-pin 33 will be carried from its home position, around to cross *d*, thereby imparting the maximum movement to said crank and rocker that is due for a single half 15 cycle of the piston. From the foregoing explanation, it is evident that if lever 26 be only slightly tilted forward from its home position, the radial center of guides 30 will only be correspondingly moved away 20 from the center of crank 33 in the direction of cross *e*, and therefore, but a corresponding slight movement only, will be imparted to crank 33 and rocker shaft 31. It is therefore evident that during the outward and 25 return stroke of piston rod 10 the movement of crank 33 and rocker shaft 31, may be varied from no movement to the maximum above described.

In the modification disclosed by Figs. 7 30 and 8 the distinction is very slight and primarily consists of employing a formerly imaginary radial center for a real supporting and guiding center, hence subscripts of the distinctions due to said modifications 35 only, are included. Lever 28^a takes the place of former lever 26. It is not necessarily forked, and is pivotally attached to frame 16 at pivotal point 20 by a large adjustment bolt 28^a. Guides 30 are omitted, 40 but instead a projecting arm is added, containing an opening in which a pivotal bolt 33^a is rigidly secured, said bolt being so located as to correspond with the radial center of guides 30 on lever 26, and also stand directly in line with crank 33 when lever 26 45 is at the same home position as lever 26 in Fig. 1. Pivotally attached to bolt 33^a is a link 34^a substantially a duplicate of link 34, except that it carries a male sleeve like 50 extension, and link 34 has its lower pivotal opening slightly enlarged in order to receive said extension and thus preserve their pivotal alinement, after which they are further secured by a pivotal bolt 38^a having a 55 spacing nut 38^b which fits slidingly against the inner side of frame 21.

The outer end of the forked connecting rod 37 is widened out slightly, and not only embraces the lower ends of both said links, 60 but fills the remainder of the otherwise unoccupied space between frames 16 and 21, thus completely guiding it as well as said links against lateral motion. Crank arm 32 is slightly modified, but by means of 65 crank 33 attaches to link 34 in so near the

same manner as in Fig. 1 as to require no further comment.

By comparing Figs. 7 and 8 with Fig. 5, it will be seen that all similar or corresponding members are in a like position. Also 70 that in Fig. 8, link 34 is entirely concealed but substantially outlined by link 34^a. Also that a forward movement of lever 26^a carries the pivotal center of bolt 33^a over identically 75 the same arcuate line as that described by the imaginary center of the radial guides shown on lever 26 in Figs. 1 and 5, and therefore, that the outer or coupled ends of links 34 and 34^a as well as that of forked connecting rod 37 will, when in motion, describe identically the same arcuate lines as if directed by guides 30 of lever 26, instead of by pivotal pin 33^a in Figs. 7 and 8, and therefore, will impart identically the same 80 movement to crank 33 and rocker shaft 31. 85 Inasmuch as I wish to place particular emphasis on my method of piston control, I have deemed it best and proper to devote a section of the specification to it exclusively as disclosed in Figs. 11, 12, 13 and 14. 90

In Fig. 11, the valve 12 is provided with a central steam inlet and chamber 50, also an exhaust outlet 51 and exhaust ports 52 and 53, the latter terminating in exhaust chambers at each end of said chest. Leading 95 from steam chamber 50 but lying slightly to one side of the chest and cylinder center, are duplicate steam ports 54 and 55 which lead to their respective ends of cylinder 8. And leading from exhaust chambers 52 and 53 respectively are duplicate exhaust ports 56 and 57 which lead to their respective ends of cylinder 8. The upper ends of said 100 exhaust ports being bored through to the aforesaid exhaust chambers, and whereby 105 their actual capacity is predetermined. The lower ends of said exhaust ports comprise narrow slot-like openings into, and extending longitudinally from the ends of the cylinder to points distant from the ends 110 of said cylinder. Fig. 11 shows steam port 54 open, and piston 9 standing at the right hand end of cylinder 8 under full steam pressure. Exhaust port 56 is closed by valve 13, but exhaust port 57 is entirely open at 115 its upper end and slightly open at its entrance to said cylinder. The greater part of said port being closed by reason of piston 9 standing over it.

Now if valve 13 be moved to the opposite 120 end of chest 12, all port openings will be reversed; steam will have an unrestricted flow through port 55 into the right end of cylinder 8, and exhaust steam will flow out of the left end of said cylinder through port 125 56 at a closely restricted maximum rate until piston 9 reaches the inner end of port 56, after which said exhaust out-flow will be gradually reduced until piston 9 comes to rest against the cylinder head, and where- 130

by the speed of said piston which has already been restricted to not over 80 ft. per minute, is then gradually reduced until it comes to rest against the cylinder head with little or not appreciable impact. As a further refinement and control of the exhaust out-flow at the end of the stroke a regulating pin 58 is adjustably inserted at the extreme outer ends of said exhaust ports, and by means of which the speed of the piston as it approaches the end of its stroke, can be absolutely governed. I do not claim the entire right to vary the movement of the rocker shaft without varying the stroke of the motor, nor the absolute right to curtailing the speed of the piston.

What I claim is:

1. A machine element adjusting mechanism comprising an intermittent grip device having a back and forth motion, a constant throw fluid pressure, cylinder and piston motor, having the usual unrestricted inlet passages, and having exhaust passages constantly restricted sufficiently to materially reduce the piston speed below that which the fluid pressure would otherwise impart to it, and which are still further gradually restricted by the advance of the piston toward the end of the stroke, in combination with means for transmitting the constant throw of the piston to the intermittent grip device, which means is adjustable to predeterminedly vary the range of movement imparted thereby to said intermittent grip device.

2. A machine element adjusting mechanism comprising an intermittent grip device having a back and forth motion, a fluid pressure, cylinder and piston motor, having the usual unrestricted inlet passages, and having exhaust passages constantly restricted sufficiently to materially reduce the piston speed, below that which the fluid pressure would otherwise impart to it, and which are still further gradually restricted by the advance of the piston toward the end of the stroke, in combination with means for transmitting motion from said piston to said intermittent grip device.

3. A machine element adjusting mechanism comprising an intermittent grip device having a back and forth motion, a fluid pressure cylinder and piston motor, having inlet passages ample to admit and maintain the full and unrestricted supply pressure upon the piston, and having narrow slot like exhaust passages extending longitudi-

nally inward from the ends of said cylinder, and constantly restricted sufficiently to materially reduce the piston speed below that which the fluid pressure would otherwise impart to it, and which are further gradually restricted by the advance of the piston toward the end of the stroke, in combination with means for transmitting motion from said piston to said intermittent grip device.

4. A machine element adjusting mechanism comprising an intermittent grip device having a back and forth motion, a rocker shaft which constitutes the immediate member for actuating said mechanism, a crank having an arm secured to said shaft for actuating it and said mechanism, a constant throw, fluid pressure, cylinder and piston motor, a piston rod extending outward from the piston of said motor, an adjustable setting lever having a pivotal support, the axis of which, is substantially in front of, and in line with said piston rod, a connecting rod leading from said piston rod and presenting its outer bearing in line with the axis of said setting lever, a member forming a direct connection between said crank and the outer end of said connecting rod, and means secured directly to said setting lever which causes the outer bearing of said connecting rod to describe an arc of a circle which, while of fixed and constant dimensions, is subject to such changes in its position as to vary and predetermine the movement of said setting mechanism, irrespective of the constant throw of the piston of said motor.

5. A machine element adjusting mechanism comprising an intermittent grip device having a back and forth motion, a fluid pressure, cylinder and piston motor, having inlet passages and in addition thereto, having narrow slot like exhaust passages extending longitudinally inward from the ends of the cylinder and which are constantly restricted sufficiently to reduce the piston speed below that which the fluid pressure would otherwise impart to it, and which are still further gradually restricted by the advance of the piston toward the end of the stroke, in combination with means for transmitting motion from said piston to said intermittent grip device.
